ELECTROMECHANICAL TRANSLATING
DEVICEOrville M. Dunning, East Orange, N. J., assignor
to Thomas A. Edison, Incorporated, West
Orange, N. J., a corporation of New Jersey

Application December 6, 1933, Serial No. 701,247

20 Claims. (Cl. 179—100.41)

My invention relates to electromechanical translating devices and more particularly to electrical phonographic recorders which are adapted to be used on recording machines and which, by reason of the nature of the uses to which they are put, must not only be extremely rugged but also must not require any appreciable adjustment after they have been put into service. An example of such use is the dictating machine of which persons who have no understanding of the mechanism are the most frequent users and in respect of which the manipulation of a few simple controls must be the entire extent of the attention required to be given to the machine by the user.

In the older forms of such machines, it has been common practice to employ a vibratable diaphragm carrying a sapphire recording stylus, the diaphragm being held in an extremely lightweight pivotally mounted sound box. Such stylus is thus movable toward and away from the record tablet and in normal operation bears against the record tablet with a pressure, due to the effective weight of the sound box, which is made just sufficient to cut the desired depth of groove. This general arrangement has been used in practically all commercial dictating machines for many years and has proven entirely satisfactory for this type of recording.

However, it has usually been found somewhat difficult to construct electrical recording devices in which this same general arrangement of parts is used. Most practical types of electromechanical translating devices do not lend themselves to the reduction of weight required by such an arrangement. In general, these devices cannot be reduced in weight to the point required by said arrangement without rendering them almost completely insensitive. For this reason most of the electrical recording devices heretofore designed for operation in the service referred to above, were arranged so that the translating device was mounted on a carriage supported in place over a record tablet support. The engraving of the record was accomplished by a stylus mounted in a small stylus arm which was pivotally supported by a light frame, which frame, in turn, was pivotally mounted on the carriage; and the stylus was connected to the translating device by means of a link so as to permit free motion of the stylus arm toward and away from the record tablet. Practically all of these devices are unsatisfactory because it is difficult to prevent rattles in the link connection without introducing undue restraint, and because, with such an arrangement, the frequency characteristic ob-

tained is usually much poorer than the characteristic which would be obtained if the translating device could be so mounted as to vibrate the stylus directly.

I have found however that there is one type of translating device which is particularly adapted for use in these electrical recorders because it has a much higher ratio of sensitivity to weight than any of the other devices with which I am familiar. This device is a special form of piezoelectric crystal, such as that described in U. S. Patent No. 1,802,782, issued to C. B. Sawyer on April 28, 1931, and entitled Piezo-electric device. Such a translating device is formed by cutting two thin slabs or sections from a homogeneous Rochelle salt crystal, cementing these two sections together with an intervening electrode of tinfoil or similar material, and cementing electrodes to the outer surfaces of the two crystal sections, substantially parallel with the center electrode. The two outer electrodes of the crystal device so formed are connected together. When a voltage is applied to this crystal device by connecting the center electrode to one side of the source of the voltage and the two outer electrodes to the other side of the source, a field is applied to the two sections of crystal in opposite directions with the result that one of said sections will tend to increase in length and the other of said sections to decrease in length. This results in a bending action similar to that exhibited by bi-metallic strips when heated. With such a construction, a much greater deflection may be obtained than with a single piezoelectric crystal element. Such a translating device is therefore extremely well suited for use in electrical recorders wherein the stylus is actuated directly by the translating device since the crystal material is light and relatively small sections thereof may be used.

It is therefore the principal object of my invention to provide an electrical recorder in which the recording stylus is applied directly to the translating device without intervening linkages and in which the depth of the groove engraved by the stylus is determined by the weight and arrangement of the translating device.

It is a further object of my invention to provide an electrical recorder wherein the translating device is a piezoelectric crystal unit of the bending type.

It is another object of my invention to provide an electrical recorder utilizing a piezoelectric crystal as a translating medium in which the

crystal is well protected against damage due to mishandling or to shock.

It is a further object of my invention to provide an electrical recorder in which the stylus is carried directly by a translating device mounted for movement toward and away from the record tablet and wherein a novel construction is provided to permit connection of the recorder to an outside source of electrical sound vibrations without the use of flexible wire connections.

It is still another object of my invention to provide a suitable electrical circuit in which the crystal unit recorder may be made to operate correctly.

15 Further objects and features of my invention will appear in the following specification and appended claims.

For a clearer understanding of my invention, reference may be had to the drawings accompanying and forming part of this specification, wherein:

20 Figure 1 is a side elevational view of a portion of a recording machine including an electrical recorder embodying a preferred form of my invention.

25 Fig. 2 is a sectional view taken approximately on the line 2-2 of Fig. 1;

Fig. 3 is a bottom plan view of the frame of the recorder and certain associated parts;

30 Fig. 4 is a sectional view taken approximately on the line 4-4 of Fig. 2, of the translating device assembly;

Fig. 5 is an enlarged perspective view showing various parts of the translating device assembly; and

Fig. 6 is a diagram showing the electrical circuit of the recorder.

The recording machine comprises a carriage 1 mounted for sliding movement on a guide rod 2. The carriage is moved by any suitable means such as a feed screw (not shown) transversely of a record tablet A which may be rotated during recording by any suitable means. The recorder is mounted on the arm 4 and comprises a frame 3 on the under side of which is secured a block of insulating material 4. A pair of brackets 5 and 6 are held in place on the block 4 by screws 5' and 6' which are insulated from the frame 3 by suitable insulating washers and bushings. The brackets 5 and 6 serve as a support for the recorder unit as well as for the bringing out of electrical connections from such unit.

The recorder unit includes a piezoelectric crystal bending unit 7 of the type described in the above mentioned U. S. Patent No. 1,802,782, issued to C. B. Sawyer on April 28, 1931. This unit comprises two sections cut from a homogeneous Rochelle salts crystal, the sections being cemented together with an intervening central electrode 7' to which one connection is made. The crystal sections are also provided with a pair of outside electrodes 7'', these two electrodes being connected together to form the other connection to the crystal unit. At one end the crystal unit 7 is cemented into a suitably formed channel in a block 8 of suitable insulating material, such as bakelite. A pair of holes 9 are drilled in the block 8 and intersect the channel which carries the crystal unit to provide for bringing out the leads from the electrodes of the crystal unit. The lead from the center electrode passes through one of these holes and the leads of the two outside electrodes pass through the other of these two holes. The block 8 is also 75 drilled at right angles to the holes 9 to receive

a pair of pivots 10 which are provided with slots 10' at their inner ends and are slightly flattened at the top. These pivots intersect the holes 9 through which the leads from the crystal unit electrodes pass and in consequence, when they are inserted, the leads are pushed into the slots 10' formed on their inner ends. The block is also suitably drilled and tapped to receive a pair of screws 11. These screws when tightened serve to clamp the split ends of the pivots 10 and thereby make a secure connection to the leads from the crystal electrodes. It will thus be seen that connections may be made to the electrodes of the crystal unit through the pivots 10 which are insulated from each other.

At the end opposite to that cemented in the block 8, a clip 12 is cemented to the crystal unit. A stylus holder 13 is suitably secured to this clip by means of screws, and carries a stylus 14. The entire crystal unit assembly is enclosed in a 20 case of strong aluminum alloy comprising a top section 15, a bottom section 16, and a rear section 23. This case is held in place by suitable screws 17 threaded into the bakelite block 8. The lower portion 16 of the case is suitably cut out 25 to allow passage of the stylus holder 13. Between the crystal unit and the enclosing casing, a pair of rubber blocks or pads 18, substantially co-extensive with the unencumbered portions of the crystal unit faces, are disposed under considerable compression.

The conical ends of the pivots 10 are adapted to fit in a pair of suitably drilled holes 19 in the brackets 5 and 6. The bracket 5 is made somewhat springy to permit insertion of the pivots 10. 35 An adjusting screw 20, threaded into the bracket 6 and insulated from the bracket 5 by a suitable insulating bushing and washer, is provided in order to adjust the tension which is applied upon the pivots of the device. For proper adjustment, 40 this screw is set so that there is substantially no play in the pivots, but so that they are not sufficiently tightly clamped to cause any binding of the translating device assembly which might prevent the recorder stylus freely following the irregularities of the record. The pivoted translating device assembly is also provided with a fin 21 arranged for coaction with a narrow cup 22 carried by the bracket 6. This comprises a stabilizing means and is explained in detail in my co-pending application Serial No. 659,743, now U. S. Patent No. 2,028,197.

The circuit with which the device is used is shown in Fig. 6. The leads from the recorder are connected to an amplifier with a resistance R in series.

In the construction outlined above, it is obvious that if the connections mentioned are made to the terminals 5' and 6' from a source of voltage such as a thermionic amplifier, this 60 voltage will be applied across the sections of the crystal unit by reason of the connections through the brackets 5 and 6, the pivots 10, and the leads of the crystal unit. By making the connections to the pivots in this way undesirable loose leads 65 are dispensed with thus making it simple to assemble and disassemble the translating unit in respect of the supporting brackets without disconnecting any wires. Furthermore, because of the high impedance of the crystal unit itself 70 which may be a substantially pure capacity of approximately .0025 mfd., any slight irregularity in a pivot resulting in a somewhat imperfect contact between the pivot and the bracket 10, would have negligible effect upon the system since in 75

no case would the contact resistances rise to values comparable with the impedance of the crystal unit.

It will also be noted that in the construction shown, the crystal unit is cemented into the holder at a point very close to the pivot so that this end of the crystal unit is held securely against translatory movement. Therefore, the maximum deflection of the crystal will occur at the end of the crystal carrying the stylus, thus providing maximum sensitivity.

The case 15, 16 about the crystal unit provides a certain amount of protection to such unit which is somewhat fragile and might be easily broken if it were exposed. The protection of the crystal unit is further increased by the inclusion of the rubber blocks or pads 18 between the case and the unit. These pads are placed under some compression and accordingly provide considerable additional support for the crystal unit, thus overcoming almost entirely the danger of breakage of the latter due to its fragility. The rubber pads 18 however have two additional functions which are extremely important in connection with the recorder herein disclosed. The first of these is that they serve to increase the effective stiffness of the crystal unit, thereby increasing its fundamental resonant frequency and increasing the range of frequencies which may be recorded. In addition, they provide a certain amount of viscous damping which serves to considerably decrease the response of the crystal unit at resonant frequencies and thereby to make the response characteristic of the recorder more uniform than might be obtained without their use.

In the structure which I have so particularly described and illustrated it will be seen that the mass of the crystal unit forms a substantial portion of the total downward biasing force on the stylus. Thus the inherently high sensitivity per unit weight of the crystal proper, hereinabove-mentioned, is not unduly sacrificed and in the complete recorder an excellent ratio of sensitivity to weight is retained; thus obviously there is permitted a full modulation of the bias (and hence of the record groove) by modest alternating voltage inputs.

Particular attention is directed to the use of the resistance R in series with the crystal unit during recording. This resistance serves to do two things: (1) to modify the frequency characteristic of the recorder so that it cuts a record groove of the type best suited for reproduction with ordinary phonographic reproducers, and (2) to hold the impedance of the combined output circuit comprising the crystal unit and the resistance, much more nearly constant than would be the case if the crystal unit alone were used. The amount of deflection which occurs in a piezoelectric crystal unit is a function only of the voltage which is applied to the unit. It is nearly independent of the frequency of the applied voltage up to the fundamental frequency of resonance of the crystal unit, over which range the compliance reaction due to the stiffness of the unit is much larger than the mass reaction. It is to be understood that if subjected to a frequency higher than that where the fundamental resonance occurs, the response of the crystal unit may be very irregular since it tends to break up and to vibrate in parts. It is therefore desirable that the fundamental resonance of the crystal unit should be made as high or slightly higher than the highest frequency to be re-

corded. The value of this resonant frequency is determined by the dimensions of the crystal unit and by its mounting. In my embodiment, I contemplate making the dimensions of the crystal such that the resonant frequency is at or above the highest frequency to be recorded. For these reasons if a sinusoidal voltage of constant amplitude at a number of frequencies throughout the range to be recorded is applied to the crystal unit, the maximum cyclic displacement of the crystal unit would be substantially constant throughout the range. If such a condition existed in a recorder it would produce a record which has been called the constant amplitude type.

It has been well established in the art that the constant amplitude type record would introduce certain difficulties which would make it almost impossible to reproduce the higher frequencies in the range. For this reason and for other considerations, it is generally accepted that the best type of phonographic record is that which is known as the constant velocity type in which the product of the maximum cyclic amplitude at any frequency and the frequency is a constant, or in which, in other words, the maximum cyclic amplitude is inversely proportional to the frequency. By the inclusion of a resistance of the proper value in series with the crystal unit, such a characteristic is obtained when a constant voltage is applied to the combination of the resistance and the crystal unit. The impedance of the crystal unit is substantially that of a pure capacity so that its impedance continually falls with increasing frequency. Therefore, if we place in series with the crystal unit a resistance which is of the same order of magnitude as the impedance of the crystal unit at the lowest frequencies to be recorded and if we apply constant voltage across the crystal unit and resistance, the voltage appearing across the crystal will be substantially inversely proportional to the frequency. As a result the amplitude of vibration of the crystal will be substantially inversely proportional to frequency, thus yielding a constant velocity type recording.

However, in some cases it is desirable, in order to get the maximum amount of recording upon a record blank for a given set of groove dimensions, to make the recorder response characteristic substantially constant amplitude below 300 cycles and constant velocity above 300 cycles. I accomplish this, where desired, by so proportioning the series resistance relative to the impedance of the crystal unit that at frequencies below 300 cycles, the resistance is less than the impedance of the crystal unit while above 300 cycles the impedance of the crystal unit is less than that of the resistance. In this way a record which approximates the constant amplitude characteristic below 300 cycles and the constant velocity characteristic above 300 cycles is obtained.

The use of a series resistor has one other additional important function in this connection. It has been well established that there is a certain value of impedance into which the power output stage of the thermionic amplifier should work in order to obtain the minimum amount of distortion. This impedance is constant for all frequencies and therefore should be a substantially pure resistance. It is always possible of course to realize any desired magnitude of resistance in the output of a thermionic amplifier by the use of appropriate transformers. However it is essential that, if minimum distortion

- from the amplifier is to be obtained, the output impedance should not vary greatly from the best value. It is obvious that by including a resistance in series with the crystal unit equal in value to the impedance of the unit at or near the lowest frequency in the range to be recorded, the variation in impedance in the output circuit is enormously decreased over that which would be obtained without the use of the resistance.
- 19 While the impedance of the crystal unit falls off rapidly with frequency, the resistance remains constant so that the maximum possible deviation from the impedance in the output circuit at the frequency at which the crystal unit and resistance are matched is somewhat less than 40%. In contrast to this, if the crystal unit only were included in the output circuit, a change of ten times in frequency would produce a change of ten times in output impedance so that this arrangement would be undesirable for use in connection with a thermionic amplifier.

Having thus described my invention, I claim:

1. An electro-mechanical translating device comprising a frame, a piezoelectric bending unit comprising a plurality of electrodes, a mounting for said unit, and a pivotal connection between said mounting and said frame, the axis of said connection being substantially parallel to said electrodes.
2. In an electrical recorder, a frame, a piezoelectric bending unit comprising a plurality of electrodes, a mounting for said unit, a pivotal connection between said mounting and said frame, the axis of said connection being substantially parallel to said electrodes and record engraving means connected to said unit.
3. An electro-mechanical translating device comprising a frame, a piezoelectric bending unit having a plurality of electrodes and mounted on said frame for free rotary movement about an axis parallel to said electrodes and located near one end of said unit, and means for transmitting vibrations connected to said unit at a point remote from said end thereof.
4. An electro-mechanical translating device comprising a frame, a translating medium comprising an active element adapted to bend upon the application of voltage thereto, and a cantilever mounting for said element pivotally connected to said frame adjacent one end of said element for movement of said translating medium in the direction of said bending.
5. In an electrical recorder, a frame, a piezoelectric bending unit, a cantilever mounting for said unit pivotally connected to said frame adjacent one end of said unit for movement of said unit in the direction of its bending, and record engraving means connected to said unit at a point remote from said mounting.
6. In an electrical recorder, a piezoelectric bending unit and means for mounting said unit for movement about an axis adjacent one end of said unit, said unit being arranged for bending in the direction of said movement, and record engraving means carried by said unit.
7. An electro-mechanical translating device comprising a translating medium having an active element adapted for bending upon the application of voltage thereto, and means for mounting said medium for movement about an axis adjacent one end of said element, said element being arranged for bending in the direction of said movement.
8. In an electrical phonographic device, a frame, a translating medium having an active

element adapted for bending upon the application of voltage thereto, a solid cantilever mounting for said element pivoted to said frame for movement of said element toward and away from a record, said element being arranged in said mounting for bending in the direction of said movement, and record engaging means connected to said element.

9. In an electrical recorder including a device for engraving oscillations in a record, said device being adapted for bias against the record and being responsive to modulations of said bias: means for producing and modulating said bias comprising a piezoelectric bending unit carrying said device, supported for unitary movement toward and away from the record, and positioned for bending in the direction of such movement.

10. In an electrical recorder including a device for engraving oscillations in a record, said device being adapted for bias against the record and being responsive to modulations of said bias: means for producing and modulating said bias comprising a piezoelectric bending unit carrying said device, pivotally supported adjacent one of its extremities removed from said device for movement toward and away from the record, and positioned for bending in the direction of such movement.

11. In an electrical recorder including a device for engraving oscillations in a record, said device being adapted for bias against the record and being responsive to modulations of said bias: means for producing and modulating said bias comprising a piezoelectric bending unit carrying said device, and a cantilever mounting for said unit pivotally supported for movement of said unit and device toward and away from the record, said unit being positioned in said mounting for bending in the direction of such movement.

12. In an electrical recorder including a device for engraving oscillations in a record, said device being adapted for bias against the record and being responsive to modulations of said bias: a piezoelectric bending unit carrying said device above the record, supported for unitary movement toward and away from the record, positioned for bending in the direction of such movement, and having a mass which provides a substantial portion of said bias.

13. In an electrical recorder including a device for engraving oscillations in a record, said device being adapted for bias against the record and being responsive to modulations of said bias: a piezoelectric bending unit carrying said device above the record, and a cantilever mounting for said unit pivotally supported for movement of said unit and device toward and away from the record, said unit being positioned in said mounting for bending in the direction of such movement and having a mass which provides a substantial portion of said bias.

14. In an electrical recorder including a device for engraving oscillations in a record, said device being adapted for bias against the record and being responsive to modulations of said bias: a piezoelectric bending unit carrying said device above the record, and a casing carrying and protecting said unit and supported for movement toward and away from the record, said unit being positioned in said casing for bending in the direction of said movement and having a mass which provides a substantial portion of said bias.

15. In an electrical recorder including a device for engraving oscillations in a record, said device being adapted for bias against the record and being responsive to modulations of said bias: a piezoelectric bending unit carrying said device above the record, a casing carrying said unit and supported for movement toward and away from the record, and means between said unit and casing to resist relative movement therebetween, said unit being positioned in said casing for bending in the direction of said movement and having a mass which provides a substantial portion of said bias.
16. An electro-mechanical translating device comprising a frame, a translating medium comprising an active element adapted to bend upon the application of voltage thereto, a cantilever mounting for said element, and a pivotal connection between said mounting and said frame comprising electrical connections to said medium.
17. In an electrical recorder, a frame, a piezoelectric bending unit, a mounting for said unit, and a pivotal connection between said mounting and said frame, said connection comprising electrical connections to said unit.
18. An electro-mechanical translating device comprising a frame, a translating medium comprising an active element and wherein the translatory action is accompanied by bending move-
- ment of such element, a mounting for said element, and a pivotal connection between said frame and said mounting comprising electrical connections to said medium.
19. An electro-mechanical translating device comprising a frame, a translating medium comprising an active element and wherein the translatory action is accompanied by bending movement of such element, a mounting for said element, and a pivotal connection between said frame and said mounting comprising a pair of coaxial pivots insulated from each other, a pair of pivot receiving members insulated from each other and adapted to coact respectively with said pivots, said pivots and pivot receiving members constituting a portion of the electrical circuit of said translating medium.
20. In an electro-mechanical translating device, a frame, a translating medium comprising an active element and wherein the translatory action is accompanied by bending movement of such element, a mounting for said element, a pivotal connection between said mounting and said frame comprising a pair of coaxial pivots insulated from each other, and an electrical circuit connected to said medium and comprising said pivots.

ORVILLE M. DUNNING.
